(75) Inventor: **Jonathan Sann**, Miami, FL (US)

* cited by examiner

(73) Assignee: **Jonathan Drew, Inc.**, Miami, FL (US)

Primary Examiner—Gary D. Watson

Assistant Examiner—RoseLynne (Ulm) Cody

(**) Term: **14 Years**

(74) *Attorney, Agent, or Firm*—Dilworth Paxson LLP; John W. Goldschmidt, Jr.; Philip J. Foret

(21) Appl. No.: **29/238,686**

(57) **CLAIM**

(22) Filed: **Sep. 19, 2005**

The ornamental design for the multi-hinged storage and display structure, as shown and described.

(51) **LOC (8) Cl.** **03-01**

DESCRIPTION

(52) **U.S. Cl.** **D3/294; D9/423**

FIG. 1 is a perspective view of a multi-hinged storage and display structure in accordance with a preferred embodiment of the present invention;

(58) **Field of Classification Search** D3/206,

FIG. 2 is a front perspective view of a multi-hinged storage and display structure in accordance with a preferred embodiment of the present invention;

D3/272–274, 294–295, 905, 414, 418, 420–423,
D3/432, 715, 721; 206/46.2, 251, 272, 823;
40/120

FIG. 3 is a back perspective view of a multi-hinged storage and display structure in accordance with a preferred embodiment of the present invention;

See application file for complete search history.

FIG. 4 is a top perspective view of a multi-hinged storage and display structure in accordance with a preferred embodiment of the present invention;

(56) **References Cited**

FIG. 5 is a bottom perspective view of a multi-hinged storage and display structure in accordance with a preferred embodiment of the present invention;

U.S. PATENT DOCUMENTS

FIG. 6 is a right perspective view of a multi-hinged storage and display structure in accordance with a preferred embodiment of the present invention; and
